UNITED STATES PATENT OFFICE.

FREDERIC COOK AND BURCHARD THOENS, OF NEW ORLEANS, LOUISIANA.

FEED-WATER REGULATOR.

SPECIFICATION forming part of Letters Patent No. 393,621, dated November 27, 1888.

Application filed February 19, 1887. Renewed May 8, 1888. Serial No. 273,262. (No model.)

To all whom it may concern:

Be it known that we, FREDERIC COOK, a citizen of the United States, and BURCHARD THOENS, a subject of the Emperor of Germany, residing at New Orleans, in the parish of Orleans and State of Louisiana, have invented new and useful Improvements in Feed-Water Regulators for Steam-Boilers, of which the following is a specification.

10 The object of our invention is to provide novel means for automatically regulating or graduating the supply of steam to the feed-pump or injector of a steam-boiler, whereby the requisite quantity of water is maintained 15 in the boiler.

10 The invention consists in the combination of devices and their mode of operation, herein-after described and claimed, reference being made to the accompanying drawing, in which 20 the figure is a vertical sectional view of a feed-water regulator embodying our invention.

25 In order to enable those skilled in the art to make and use our invention, we will now describe the same in detail, referring to the drawing, wherein—

30 The numeral 1 indicates a cylindrical or other suitably-shaped casing having an upper pipe-connection, 2, with the steam-space of a steam-boiler, and a lower pipe-connection, 3, 35 with the water-space of the boiler. The lower end of the casing is provided with a detachable cover, 4, and the upper end of the casing is provided with a screw-plug, 5, to which is coupled the blow-off cock 6, and the pipe 7 leading to the feed-pump or injector of the boiler, which pump or injector it is not necessary to illustrate.

40 To the screw-plug 5 is secured the upper end of a vertical pipe, 8, having near its upper portion a series of longitudinal slots, 9, and at its lower end a screw-plug, 10, carrying a vertical tube, 11, contracted at its upper end above the slots 9, and depending below the plug 10 to enter a well, 12, formed by a tube, 13, depending from the bottom wall of a hollow float-cylinder, 14, provided with a guide, 15, in the form of a tube having internal ledges, 16, which bear against and slide upon the pipe 8, said tube being connected by arms 17 or 50 otherwise with the hollow float-cylinder. The top portion of the casing 1 is interiorly provided with a circular or other shaped guard-

flange, 18, surrounding the upper end of the float and extending below the steam connecting pipe 2.

55 To the pendent tube 13 or other part of the float is secured a weight-receptacle, 19, or its equivalent, for properly submerging the float in the water contained in the casing. The casing is provided with a water-gage, 20, to 60 indicate the level of the water in said casing, and as the level of the water in the latter is supposed to be the same as that in the boiler the water-level therein can also be observed. The vertical sliding movement of the guide-tube 65 15 more or less closes the slots 9 of the pipe 8. The steam entering the pipe-connection 2 passes around and under the guard-flange 18, through the open portions of the slots 9 to the steam-pipe 7, leading to the feed-pump or injector of the boiler. This causes a suction or 70 siphonage of the condensed water from the well 12 and float 14, and keeps them free of the same. By closing the valve 21 in steam-pipe 7 and opening the blow-off cock 6 the 75 condensed water in the float can be blown out before starting the steam-pump and regulator, after which the collection of condensed water is so trifling that it will pass with the steam into the cylinder of the steam-pump without 80 harm. The buoyancy of the float will, by controlling the slots 9, regulate the flow of steam to the steam-pump or injector, and hence the speed of the latter will be regulated according to the requirements of the boiler.

85 The only working parts in this regulator where friction exists is where the guide-tube 15 works on the pipe 8; but as it is always either in steam or condensed water no deposit from the water in the boiler can be deposited 90 on the working-surfaces.

95 In case the boiler should prime and water pass over through the pipe-connection 2 into the regulator, it strikes the guard-flange 18 and falls into the regulator outside the hollow float, consequently no water from the boiler can ever enter the float except condensed steam.

100 The more or less weight in the receptacle 19 changes the relation of the water-level to the area of the steam-openings 9 in vertical pipe 8, so that the float can be set to admit the necessary steam to pumps to maintain a uniform water-level, even if the pump is disproportioned to size of boiler.

Having thus described our invention, what we claim is—

1. The combination, in a feed-water regulator, of a laterally-perforated pipe with a vertically-movable float open at its upper end and receiving within it steam from the boiler, and the rising and falling movements of which govern the flow of steam to the pump or injector through a part of the float, gradually opening and closing the perforations in the said pipe, substantially as described.
2. The combination, with a feed-water regulator, of a sliding float open at its upper end, and having an attached interior tube working over steam-openings to control the speed of the pump, substantially as described.
3. The combination, with a feed-water regulator, of the hollow float open at its upper end, the steam pipe having steam-openings and on which a guide of the float works, and the steam-siphonage for the float, substantially as described.
4. The combination, with a feed-water regulator, of a hollow float open at its upper end, and a steam siphon-tube worked by the flow of steam around its point to free the float of condensed water, substantially as described.

5. The combination, with a feed-water regulator and a float having an upper open end, of a pendent guard-flange to prevent the flow of steam striking the float, and to cause the condensed water to fall outside the float, substantially as described.

6. The combination, with the casing, of the pendent tube having longitudinal slots, a hollow float having an attached guard acting to more or less open and close the slots by the rising and falling movements of the float, substantially as described.

7. The combination, with the casing, of the pendent tube having slots, a hollow float having a well at its lower end, a guide secured to the float and working over the slots to more or less close the same, and a steam siphon-tube arranged in said slotted tube and entering the well of the float, substantially as described.

In testimony whereof we affix our signatures in presence of two witnesses.

FREDERIC COOK.
BURCHARD THOENS.
